UNITED STATES PATENT OFFICE.

LUCIUS B. WOOTTON, OF JACKSONVILLE, FLORIDA.

HACKLING MACHINE.

Application filed November 11, 1922. Serial No. 600,361.

To all whom it may concern:

Be it known that I, LUCIUS B. WOOTTON, a citizen of the United States, and a resident of Jacksonville, in the county of Duval and State of Florida, have invented a new and Improved Hackling Machine, of which the following is a full, clear, and exact description.

This invention relates to hackling machines, and has for its primary object to provide an improved construction which will simplify the process of hackling and cleaning cabbage palmetto and similar articles.

Another object of the invention is to provide a machine wherein the fiber may be secured from the palmetto boots, jackets, leaves and stems by one operation.

A further object of the invention is to provide a hackling machine wherein not only may fiber be secured by one operation, but a large proportion may be secured with a minimum effort.

In the accompanying drawings—

Figure 1 is a side view of part of the hackling machine disclosing an embodiment of the invention;

Figure 2 is a sectional view through Figure 1, approximately on line 2—2.

Figure 3 is a sectional view through Figure 4, on line 3—3;

Figure 4 is a plan view of two sections of the hackling wheel shown in Figure 2;

Figure 5 is an enlarged detail fragmentary sectional view through Figure 2 on line 5—5;

Figure 6 is a sectional view through Figure 5 approximately on line 6—6.

Heretofore in securing fiber from the cabbage palmetto, it has been necessary to boil the raw product from forty-five to fifty hours, and then pass the same through the hackling machine twice to secure the desired hackling and cleaning thereof. This

double hackling injures certain of the fiber, and, consequently, the proportion of fiber, secured is comparatively small compared to the one operation hereafter described. In the present invention there is provided a

hackling machine which with one boiling and one hackling operation will secure the desired fiber, and, at the same time, remove the dirt and produce a finished fiber ready for use.

When hackling a given quantity of palmetto, the palmetto boots or leaves are

grasped at one end by the operator, while the other end is inserted into the hackling machine so that a portion thereof, usually about one-half, comes in contact with the teeth of the hackling machine. This results in shredding of approximately one-half of the boot or leaf. When this shredding action has been carried on as long as the operator thinks necessary, or until the inserted end is in shreds, the operator withdraws the boot or leaf from the machine and reverses his grasp thereon and inserts the unshredded end while holding the shredded part of the boot or leaf. In this way the unshredded part of the boot is hackled and shredded so that the entire boot or leaf is reduced to a shredded condition. According to the present invention, the boot or leaf as it is shredded is operated on by the water jets hereinafter fully described which are projected with considerable force against that part of the boot being shredded whereby it is cleaned at the same time that it is reduced to shreds. This cleaning and shredding action takes place at both ends of the boot so that the entire boot is shredded and clean. In this process certain merchantable fiber is necessarily cut off or torn from the leaf or boot which is being hackled, although the portion still held in the hand of the operator is firmly retained therein and is eventually removed when the hackling operation is complete. The present invention is so formed as to provide means for recovering the lost merchantable fiber though it will be understood that the majority of the merchantable fiber is retained by the hand of the operator. Heretofore, the fiber torn from the boot by the hackling machines was lost completely and discharged from the machine with the pulp and waste.

In the present invention, a foraminous belt has been provided whereby this lost fiber may be recovered with but little effort and, consequently, the present invention produces a larger amount of merchantable fiber from a given quantity of palmetto boot than the machine heretofore used.

Heretofore, all the waste matter which was not fiber in the ordinary sense of the word, as understood by those in the business, but which was so finely shredded as to constitute mere hairs or fine shavings, was lost by reason of being deposited with dirt and waste material. These fine shreds or shav-

ings were commercially unsalable. In the present invention, means have been provided for cleaning and recovering these hairs or fine shreds. This particular product, 5 namely, the fine shreds or hairs are valuable, not for the same purpose as the principal shreds retained in the operator's hand, but are valuable as a substitute for hair in the manufacture of plaster board and for other 10 similar uses. This saving of the fine hairs or shavings, takes care also of the very short fibers which may be used for different purposes, as for instance, in the manufacture of plaster boards.

15 In the accompanying drawings, a machine embodying the invention is illustrated and is constructed in such a manner that by one hackling operation a maximum amount of fiber may be recovered with a minimum effort. The principal fiber is recovered by the hand of the operator and the remaining fiber recovered through the action of a foraminous belt and other parts hereinafter fully described.

20 Referring to the drawings by numerals, 1 indicates a frame of any desired kind which may be of any suitable length, and on this frame 1 any desired number of hackling drums 2 may be mounted and driven by any 25 suitable source of power. In Figure 1, two drums have been shown connected to a driving shaft 3, which is operated by a belt 4, which belt receives power from any suitable source. Each of the drums 2 is provided with a hood or casing 5, which entirely encloses the drum except at the bottom and at the entrance or feed opening 6. The hackling drums 2 are provided with a 30 number of plates 7, each plate having a row 35 of sharpened pins or teeth 8, said teeth being staggered as indicated in Figure 4, so as to produce a better hackling action. The plates 7 may be secured together by bands or in any other desired manner so as to complete 40 the drum structure, which in turn is secured in any suitable manner to end members 9, said end members being rigidly secured to the shaft 3. The unshackled boots 45 are placed in entrance of opening 6 by the operator who retains one end in his hand. A feeding and guiding chute 10 is arranged adjacent each drum 2 and extends inwardly from the opening 6.

50 When a quantity 11 of palmetto is to be shredded, it is placed in position, as shown in Figure 2, and as it is held by the operator, it is broken up and shredded by the pins or teeth 8 of the drum 2. During this operation, the operator retains practically all of 55 the good fiber except the shorter fibers, and the fibers which are broken by action of the teeth. In this shredding, the pulp and dirt are both removed or rather loosened up, and in order to remove the same, a plurality of 60 jets of water are provided. Preferably a pipe 65

12 is provided with a number of apertures facing the chute 10 so that the water will strike the material 11 as it is being shredded and wash the dirt and objectionable matter therefrom as the teeth perform their function. In order to provide the desired washing action in addition to wetting the material, the water sprayed from the pipe 12 is preferably discharged at a comparatively high pressure, as, for instance, fifty pounds 70 per square inch. It will thus be seen that the water not only wets the fiber and allows it to be hackled in a better manner, but acts in a mechanical way to wash out objectionable matter. The hackled and washed 75 palmetto is retained in the grasp of the operator's hand except such as is torn therefrom by the shredding teeth and passes down the chute and is discharged onto the upper run of the belt 13.

80 It will be noted from Figure 2 that by reason of the speed of rotation of the drum 2 and the action of the water, the merchantable fibers torn from the grasp of the operator move over to approximately point 90 14 on the belt, while the dirt and pulp remain at approximately the point 15 until the water washes the dirt downwardly and out through the bottom member 16.

85 This arrangement causes the dirt and pulp 95 to be automatically separated from the merchantable fiber wrenching from the grasp of the operator and when the matter on the belt 13 is discharged at the end of the belt, the fiber will be discharged at one point and the pulp at another, and the loose dirt will pass with the water downwardly into the member 16. The belt 13 may be of any suitable foraminous material which will allow 100 the water, dirt and pulp to pass freely 105 therethrough but which will retain the merchantable fiber lost from the operator's grasp. The desired form of belt is shown particularly in Figures 2, 5 and 6, from 110 which figures it will be seen that the belt 115 is made up of side endless chains 17 and 18 which pass over sprocket wheels near each end of the machine, there being two sprocket wheels at each end so that an even proper drive will be provided. Connected with 120 these two endless chains is a central portion or body of the belt which consists of a number of tubes and wire mesh covering therefor held in place as hereinafter fully described. The respective chains 17 and 18 are provided at intervals (as for instance, twelve inches) with an attaching facing plate 21 on the inside of the chain. These facing plates 21 are of metal and formed 125 with cones 22 which are drilled preferably with tapered holes to admit the respective cotter pins 23. On these cones are positioned the respective tubes or pipes 20 which for practical purposes, may be one inch in 130 outside diameter and which at each end are

drilled for receiving the respective cotter pins 23 so that these tubes are firmly held to the cones and form a foundation or support for the wire mesh 19. Arranged preferably centrally of the respective tubes 20 is a third cotter pin which is provided particularly for holding the wire mesh 19 on the bed of tubes. The wire mesh 19 is laid over this bed of tubes and fastened to it with a set of cotter pins 24 as well as by the end cotter pins 23 which are forced through the wire mesh so that the heads will project therefrom. The wire mesh is fastened to these cotter pins by utilizing and lacing in through the wire mesh and through the head of the cotter pins a very stiff, strong wire 25 for each series of cotter pins, said wire extending the entire length of the belt. The wire mesh 19 may be of any desired mesh, as for instance, one-fourth of an inch. The function of the wire mesh is to catch the pulp and the shreds of fiber and support these and carry them off, at the same time, permitting the water to run away. Below the belt 18 is arranged a trough 16 which is an inclined trough running the entire length of the conveyer belt and preferably having a drop of about twelve inches whereby the water passing through the conveyer will be caught and directed to a suitable discharge point. It will be noted that by means of the separation of the fiber and pulp as the hackled material is disposed on the belt, the fiber will be discharged at a different point from the pulp so that there is no need of a manual separation.

After the shredding operation above described, the fiber is dried and soaked in paraffin oil. After this has been done, it is assorted into lengths, combed and tied in bundles, ready for shipment.

What I claim is:-

1. A hackling machine, comprising a hackling drum provided with comparatively thin teeth, means for holding matter to be hackled adjacent said drum so as to permit said teeth to enter said matter and pass through part thereof for shredding the same, means for directing a spray of water under appreciable pressure against said matter as it is being operated upon by said teeth, and traveling means for receiving the hackled material from said matter,

said means acting to discharge the material disposed thereon at a point distant from 55 said drum.

2. A hackling machine, comprising a hackling drum provided with comparatively thin teeth, a chute for directing matter to be hackled to a point adjacent said drum whereby it is entered and shredded by said teeth, and means for directing water under high pressure against the matter to be hackled during the hackling operation.

3. A hackling machine of the character 65 described, comprising a hackling drum, a guide for directing material to be hackled, means for discharging water against the material being hackled during the hackling operation, and a foraminous belt for receiving 70 fiber torn from the material being hackled during the hackling operation, said material being sprayed over said belt according to its weight, so that the lighter fiber will automatically group itself on one side 75 of the belt and the dirt and heavier pulp will be disposed on the opposite side of the belt.

4. A hackling machine, comprising a 80 hackling drum formed with shredding teeth, means for supporting a palmetto boot or leaf adjacent said teeth while one end thereof is held by an operator, means for washing the boot as it is hackled so that the fiber retained in the hands of the operator will be washed and the fiber torn from the boot by said teeth will be also washed, and a foraminous carrier for receiving the fiber torn from said boot while the dirt and water passes therethrough, said carrier acting to 90 discharge the fiber deposited thereon at a distant point.

5. In a hackling machine of the character 95 described, means for hackling a boot or leaf of palmetto cabbage, said means tearing certain of the fiber from the boot or leaf during the hackling operation, means for discharging water under pressure against said fiber as it is hackled, and a foraminous carrier for receiving the fiber torn from said 100 boot or leaf, said carrier acting to discharge the fiber deposited thereon at a given point while allowing the dirt and water to pass therethrough.

LUCIUS B. WOOTTON.
